GASOLINE PUMP NOZZLE

Eliot F. Noyes, New Canaan, Ernest M. Bevilacqua, Wilton, and Robert E. Graf, New Canaan, Conn., assignors to Mobil Oil Corporation, a corporation of New York

Filed July 1, 1966, Ser. No. 2,898

Term of patent 14 years

(Cl. D91—1)

FIG. 1 is a perspective view of a gasoline pump nozzle, showing our new design.

FIG. 2 is a rear side elevational view thereof.

FIG. 3 is a top plan view thereof.

The dominant features of our design reside in the portions shown in full lines.

We claim:

The ornamental design for a gasoline pump nozzle, as shown and described.
